John L. Jones, of Slatington, Penn.

Assignor to Himself & A. Mc Dowell,
Letters Patent No 1252, dated June 12, 1860.

The schedule referred to in these Letters Patent and making part of the same.

To all whom it may concern,

Be it known that I, John L. Jones, of Slatington, Lehigh County, Pennsylvania, have invented or produced a new and original design for an ornamental ridge for roofs, and I do hereby declare the following to be a full, clear, and exact description of the same, reference being had to the accompanying drawing, which represents a portion of the ridge in perspective.

A. and A' are the two inclined side plates of the ridge secured to the cylindrical rib B, to the top of which are attached pointed projections c. c. of the form represented in the drawing.

I claim the ornamental design for a ridge for roofs, represented in and by the accompanying drawing.

In testimony whereof, I have signed my name to this specification in the presence of two subscribing witnesses,

Witnesses. {
